UNITED STATES PATENT OFFICE.

CHARLES F. LARZELERE, OF FLINT, MICHIGAN, ASSIGNOR OF ONE-HALF TO EZARIAH D. GORDNER, OF FLINT, MICHIGAN.

RAZOR-BLADE-STROPPING HOLDER.

Application filed July 9, 1921. Serial No. 483,396.

To all whom it may concern:

Be it known that I, CHARLES F. LARZELERE, a citizen of the United States of America, residing at Flint, in the county of Genesee and State of Michigan, have invented certain new and useful Improvements in Razor-Blade-Stropping Holders, of which the following is a specification, reference being had therein to the accompanying drawings.

10 The invention relates to razor blade holders designed for use in the stropping of detachable blades of safety razors and it is the object of the invention; first, to obtain a construction with which the blades may be 15 readily engaged and disengaged; second, one which may be easily carried in the box of the safety razor; and third, one which utilizes the handle of the razor and therefore dispenses with the necessity of a separate 20 handle. With these and other objects in view the invention consists in the construction as hereinafter set forth.

In the drawings:

Figure 1 is a perspective view of the 25 blade holder with a blade in engagement therewith;

Figure 2 is an elevation of the holder in open position;

Figure 3 is a similar view of the holder in 30 closed position;

Figure 4 is an enlarged cross-section showing the blade clamped in the holder.

With certain constructions of safety razors now in general use, the handle of the 35 blade holder is detachable, being provided with a screw-threaded socket for engagement with a correspondingly threaded shank on a cooperating member. With my improvement I utilize this handle as a part of 40 the stropper and to this end form the blade-holding device with a threaded shank engageable with the socket on the handle. By thus dispensing with a separate handle, the blade-holding means may be easily carried 45 in the box or holder for the razor, which is a great convenience.

My improved holder consists essentially 50 in a pair of members A and B having a hinge connection C, which permits of folding the same one upon the other and upon opposite sides of the blade. The member A has secured thereto the threaded stud D, which is engageable with a handle such as E of the usual holder. The stud D is attached to the 55 member A through the medium of a longi-

tudinally centrally slotted shank F, said shank having a shoulder G against which the handle is screwed. The member B is cut away at H to pass over the shank F, but slightly overlaps said shank and is engageable by a 60 longitudinal movement with a slot I in the end thereof. To permit of this longitudinal movement the member B is provided with eye members C', which engage the hinged pivot rod J between the eye members C' on the member A, and the members C' are of slightly less width than the spaces between the members C'. Therefore, the member B may be moved longitudinally upon the pivot rod J a sufficient distance to engage or dis- 70 engage the same from the slot I. There is also provided a spring K sleeved upon a portion of the rod J and abutting with its opposite ends against the shoulders L and M respectively upon the members A and 75 B so as to yieldably force the member B in a direction to engage the slot I. This same spring K may be used as a torsion spring for swinging the member B towards open position, so that whenever said member B is 80 disengaged from the slot I, it will automatically open.

Where the stropper is used with perforated blades, these are held in position by stud flanges N struck outward from the 85 member A and registering apertures O in the member B. The apertures O are sufficiently enlarged to permit of the endwise movement of the member B in engaging and disengaging the slot I. I also preferably 90 provide a cloth lining for the members A, B to form a bearing for the blade and a protection for the inner edge thereof. This cloth lining P has a flap which is cemented or otherwise secured to one of the members 95 such as A, and a loose flap P' which may be folded over the blade.

With the construction as described, in use, the handle E of the razor holder is screwed upon the stud D, after which the blade may 100 be placed upon the flange studs N within the folded flap of the lining P and then the member B may be folded over in clamping position. The end of the shank F is bevelled, as indicated at F', so that in pressing 105 the member B towards closed position it will be moved longitudinally against the tension of the spring K and as soon as it is in registration with the slot I, will snap into engagement therewith. This will clamp the 110

blade securely and will permit of stropping the same on an ordinary razor strop in the usual manner. When the stropping is completed, the operator by pressing his thumb 5 against the lower end of the member B will force the same out of engagement with the slot I, whereupon the torsional tension of the spring K will immediately swing the member B to open position. The device is 10 therefore one which is easily manipulated and as before stated, when not in use, may be readily stored within the box of the razor holder.

While I have described my construction as 15 utilizing the handle of the holder, it is obvious that it could be provided with a separate handle if so desired.

What I claim as my invention is:

1. A razor blade stropping holder comprising a pair of hingedly connected clamping plates providing for a slight relative longitudinal movement, a handle member secured to one of said plates, a latch keeper on said plate for engaging the opposite plate 25 by a longitudinal movement thereof, and means for yieldably forcing the latter plate into engagement with said keeper.

2. A razor blade stropping holder comprising a pair of hingedly connected clamping plates providing for a limited relative longitudinal movement upon the hinged pivot, resilient means for yieldably holding said plates in one position of relative longitudinal adjustment, a handle secured to one 35 of said plates, and a latch keeper with which the swinging plate is automatically engaged when in clamping position by said resilient means.

3. A razor blade stropping holder comprising a pair of hingedly connected clamping plates providing for a relative longitudinal movement on the hinged pivot thereof, resilient means for yieldably pressing said plates towards open position and towards one limit of relative longitudinal adjustment, a handle member secured to one of said plates, and a keeper with which the other of said plates is engaged when in clamping position and held in engagement 45 by said resilient means, said plate being disengageable from its keeper by a longitudinal movement thereof and being automatically swung towards open position by said resilient means.

5. A razor blade stropping holder comprising a pair of hingedly connected clamping plates, means on one of said plates for engaging the same with the handle of the razor holder, and a latch for holding the other of said plates in clamping position, disengageable by a relative longitudinal movement of said clamping members.

6. A razor blade stropping holder comprising a pair of hingedly connected clamping plates, a screw-threaded stud secured

to one of said plates and engageable with the handle of the razor holder, and means for detachably holding the other plate in clamping position, disengageable by a relative longitudinal movement of said clamp- 70 ing members.

6. A razor blade stropping holder comprising a pair of hingedly connected clamping plates, a threaded stud having a longitudinally slotted shank engaging one of said plates, said stud being engageable with the handle of the razor holder, means permitting a relative longitudinal movement of the other of said clamping plates on the hinge connection thereof, said shank being provided with a slot with which said last-mentioned plate is registered in clamping position, and resilient means for forcing said plate into engagement with said slot to retain the same in clamping position. 80

7. A razor blade stropping holder comprising a pair of plates having inter-engaged eye members, a pivot rod engaging said eye members to form a hinge connection, said eye members on the respective plates being longitudinally spaced apart to permit of a relative longitudinal movement on said rod, a spring sleeved on said rod and engaging eye members of the respective plates for yieldably forcing said plates towards one limit of longitudinal adjustment and for also exerting a torsional stress, tending to swing said plates towards open position, a handle attachment having a longitudinally slotted shank engaging one 100 of said plates, the end of said shank being slotted and bevelled to form a latch keeper for the other of said plates.

8. A razor blade stropping holder comprising a pair of hingedly connected clamping plates, providing for a relative longitudinal movement on the hinge pivot thereof, struck out portions on one of said plates for engaging apertures in the razor blade, registering apertures in the other of said plates enlarged to permit of a relative longitudinal movement of said plates, resilient means for yieldably pressing said plates toward opened position and towards one limit of relative longitudinal adjustment, a handle secured to one of said plates and a latch for engaging the opposite plate held in engagement by said resilient means and disengageable by longitudinal movement thereof, said last mentioned plate being automatically swung towards open position by said resilient means. 110

9. A razor blade stropping holder comprising a pair of hingedly connected clamping plates, providing for a relatively longitudinal movement, a handle member secured to one of said plates, a latch keeper on said plate for engaging the opposite plate by a longitudinal movement thereof, means for yieldably forcing the latter plate into en- 120

gagement with said keeper, and means for yieldably holding said plates in open position when said plates are not engaged by said keeper.

5 10. A razor blade stropping holder comprising a pair of hingedly connected clamping plates, providing for a limited relative longitudinal movement upon the hinged pivot thereof, spring means mounted on 10 said hinged pivot for yieldably holding said plates in open position and in one position of relative longitudinal adjustment, and a latch keeper on one of said plates cooperating with said spring means to form a snap

engagement of said plates when in clamp- 15
ing position.

11. A razor blade stropping holder comprising a pair of hingedly connected clamping plates, means on one of said plates for removably engaging the same with the handle of the razor holder, and a latch for holding the other of said plates in clamping position disengageable by a relative longitudinal movement of said clamping members. 20

In testimony whereof I affix my signature. 25

CHARLES F. LARZELERE.
